CLAIM

The ornamental design for a wire bundling support device, as shown and described.

DESCRIPTION

FIG. 1 is a front, top and left side perspective view of a wire bundling support showing my new design;

FIG. 2 is a front elevational view thereof, the rear elevational view being identical;

FIG. 3 is a top plan view thereof;

FIG. 4 is a bottom plan view thereof; and,

FIG. 5 is a left side view thereof, the right side view being a mirror image.
